UNITED STATES PATENT OFFICE.

JULIUS SCHMUTZ, OF LOUISVILLE, KENTUCKY, ASSIGNOR TO SCHMUTZ MANUFACTURING COMPANY, INCORPORATED, OF LOUISVILLE, KENTUCKY.

ARTICLE OF MANUFACTURE.

Application filed March 5, 1924. Serial No. 397,048.

This invention relates to a new article of manufacture which is especially adapted for use in connection with the making of printing plates.

5 Another important object of the invention is to provide an article of manufacture which is of such a construction as to permit the formation of the desired printing characters thereon, means being provided for retaining the printing characters formed on the article against accidental displacement.

10 Another important object of the invention is to provide an article of manufacture which is constructed of a pliable material and has embedded therein a reinforcing element for the purpose of holding the same in a substantially rigid manner, further tending to prevent the spreading or lengthening of the article while the same is being used as

20 a printing plate.

A still further object is to provide an article of manufacture which is adapted for use as a printing plate wherein a pliable back is associated with the article for preventing the creeping or slipping of the same when it is in position on the printing cylinders.

25 A further object is to provide an article of manufacture of the above mentioned character, which is simple in construction, inexpensive, strong and durable, and further well adapted for the purposes for which it is designated.

30 Other objects and advantages of this invention will become apparent during the course of the following description.

In the accompanying drawing forming a part of this specification and in which like numerals designate like parts throughout 40 the same,—

Figure 1 is a longitudinal sectional view of one form of my invention.

Figure 2 is a similar view showing the same with a rubber backing associated therewith.

Figure 3 is a longitudinal section of another form.

Figure 4 is a similar view with the rubber backing shown in connection therewith.

50 Figure 5 is still a further form.

Figure 6 is a view similar to Figure 5 with a rubber backing associated therewith.

Figure 7 is a plan of a printing plate formed from my article of manufacture

showing the same in a process of forming the printing characters thereon.

In the drawing, wherein for the purpose of illustration is shown the preferred embodiment of my invention, the numeral 1 designates a layer of rubber and the same 60 has embedded in the rear face thereof the metallic reinforcing plate 2. The purpose of providing the reinforcing plate is to prevent the spreading and lengthening of the printing plate which is formed from my article of manufacture. It is to be understood that the desired printing characters may be cut in the front face of the layer of rubber in any suitable manner. To prevent the printing plate from creeping or slipping on the printing cylinder of a printing machine while the same is in use, a rubber backing, such as is illustrated by the numeral 3 in the drawing, is vulcanized or otherwise secured to the rear face of the layer of rubber and 70 this construction is clearly illustrated in Fig. 2 of the drawing.

In the form shown in Figs. 3 and 4 of the drawing the base layer 1 has vulcanized on its front face a layer or rubber such as is shown at 4. With a printing plate constructed from the material shown in Figs. 3 and 4 the printing characters are adapted or may be formed in the front face of the upper layer of rubber 4. In Fig. 3 the article is 80 shown without the rubber backing whereas in Fig. 4 the rubber backing is included. It is to be understood that in the formation of the printing characters on the article shown in Figs. 3 and 4, the characters are adapted 85 to be cut in the upper layer of rubber 4, for its entire depth so that the same will be supported by the base layer of rubber 1.

In Figs. 5 and 6 of the drawing a still further form is shown wherein the article 90 comprises the base layer of rubber 1, the perforated metal reinforcing sheet 2 which is embedded in the rear face of the base layer, and the upper layer of rubber 4. However, a suitable strip of canvas such as 100 is shown at 5 in the drawing, is adapted to be interposed between the base layer 1 and the top layer 4, and held therein in any suitable manner. In the formation of the printing characters on the printing plate constructed from the article shown in these 105 last mentioned figures, it will be understood that the desired printing characters are cut

from the top layer of rubber 4 for its entire depth, so that the printing characters will be supported by the upper surface of the canvas strip 5. The rubber backing, such as is shown at 3, in the drawing, is also adapted to be used in conjunction with the form above described, and is clearly illustrated in Fig. 6 of the drawing.

In Fig. 7 I have illustrated a printing plate which is in the process of having the printing characters formed thereon and the particular form shown in this figure illustrates that the printing characters A are cut through the top layer of rubber 4 and will be supported by the strip of canvas 5. In the formation of these printing characters, any well known machine for this particular purpose may be used or else a suitable hand tool may be used, and I do not wish to limit myself to the particular manner in which the printing characters may be formed.

A further step which may be taken if desirable, resides in chemically treating the finished plate after the printing characters have been formed thereon, the purpose of this step being to prevent the use of printers' ink and cleaners used to clean inks from plates and which has heretofore caused the deterioration of the rubber printing characters, thus causing the further utility of the printing plate with the characters thereon to be destroyed. The chemical treatment of the printing characters on the printing plate formed from my article of manufacture will furthermore prevent any possibility of the characters from dropping off or causing to be separated from the canvas strip thereby assuring the durability of my device and at the same time assuring the holding of the characters on the strip of canvas. It will, of course, be understood that it is not necessary to include the chemical treatment in order to obtain the good results, but if desired, this step may be included.

The articles of manufacture forming my invention and shown in the various forms in the drawing are adapted to come in long sheets or strips and may be cut to the desired length or size when it is desired to use the same in a printing machine. Furthermore, with an article of manufacture of the above mentioned character, the printing characters desired may be formed thereon in an easy and efficient manner, thus enabling

the use of my article for any desired purpose. Preferably by having a printing plate constructed from my article of manufacture, the same will be used in the printing of textile materials, such as bags or the like, and it is a well known fact that the impression obtained by use of rubber printing characters is better than that which is ordinarily obtained by electrotype plates now commonly used.

As heretofore stated, the purpose of providing the article of manufacture with the reinforcing plate which is embedded in the rear face thereof is to prevent the spreading or lengthening of the printing plate while the same is in position on the printing cylinder and subject to the continual pounding and pressure of the printing operation. The provision of the rubber backing will also prevent the creeping or slipping of the completed printing plate on the printing cylinder and will also enable a cheaper reinforcing material to be used.

From the foregoing description of the construction of my improved device, it will be seen that I have provided a simple, inexpensive and efficient means for carrying out the objects of the invention, and while I have particularly described the elements best adapted to perform the functions set forth, it is obvious that various changes in form, proportion, and in the minor details of construction may be resorted to, without departing from the spirit or sacrificing any of the principles of the invention.

Having thus described my invention, what I claim is:

A printing unit comprising a parallelopiped metal plate having openings passing therethrough, the side wall surfaces of the openings from end to end of the openings and between the opposite side surfaces of the plate being disposed at right angles to the opposite side surfaces of the plate, a layer of rubber mounted upon one side surface of the plate and completely covering said surface and having projections completely filling the openings in the plate, a layer of canvas applied to the surface of said layer of rubber and a second layer of rubber applied to the outer surface of the layer of canvas.

In testimony whereof I affix my signature.

JULIUS SCHMUTZ.
